UNITED STATES PATENT OFFICE.

CLELAND DAVIS, OF THE UNITED STATES NAVY, ASSIGNOR TO ORDNANCE DEVELOPMENT COMPANY, A CORPORATION OF DELAWARE.

AEROPLANE-GUN.

1,108,714.

Specification of Letters Patent. Patented Aug. 25, 1914.

Application filed August 22, 1911. Serial No. 645,365.

To all whom it may concern:

Be it known that I, CLELAND DAVIS, commander, United States Navy, a citizen of the United States, serving on board the 5 U. S. S. *Mississippi*, stationed at Provincetown, Massachusetts, have invented certain new and useful Improvements in Aeroplane-Guns; and I do hereby declare the following to be a full, clear, and exact description of the invention, such as will enable others skilled in the art to which it appertains to make and use the same.

It having been demonstrated that it is practicable to navigate the air under normal atmospheric conditions, and while as yet the practice is too hazardous for ordinary commercial purposes, still air craft have already become a part of the military equipment of most of the civilized nations, and 20 those of the heavier than air type have been found to be specially useful for both naval and military purposes. They have, however, so far developed little, if any, offensive value, it being obviously impossible to strike 25 a comparatively small target, such as the hull of a battleship, the vulnerable point of a fort, or even a large building, by merely dropping explosive from a high altitude. This might be possible if the air craft was 30 close to the target, but such proximity would result in the almost certain shooting of the aviator, while objects dropped from a great height would partake of the motion of air craft, and it would be very difficult 35 to land them with any degree of accuracy. Furthermore, the mere dropping of a high explosive on the deck of a ship, or a fort, would occasion very small damage, for the force of the explosive would ordinarily, 40 aboard ship, be confined to the region above the protective deck, and little damage would be done from such explosion.

In order to secure the desired velocity to penetrate even thin armor, or a protected 45 position anywhere, the explosive would have to be contained in a projectile, and this projectile would have to be propelled with sufficient velocity to penetrate said armor. It would be impracticable to drop 50 an explosive from such a great height as would cause it, under the influence of gravity alone, to obtain said velocity; and moreover, it would be impracticable to aim a projectile dropped from such a height with 55 any reasonable degree of accuracy. For

these reasons, therefore, in order to successfully attack a ship with explosive from an air craft, it is necessary that the explosive shall be contained in a projectile with walls thick enough to penetrate the protective deck without breaking up, and that the projectile shall have sufficient velocity to enable it to be directed with accuracy, and to enable it to penetrate when striking. This can only be accomplished by discharging 60 the projectile from a gun. In order for a gun to be effective for such purposes, it must comply with the following conditions:—(1) It should be of caliber sufficiently large to discharge a projectile carrying a considerable quantity of explosive. 65 (2) It should be capable of giving a muzzle velocity to the projectile that would enable aimed shots to be fired at distances of 2,000 yards, or more. (3) It should be so designed that the shock of recoil will bring little, or no strain upon the structure of the 70 aeroplane.

In order to meet the above conditions, I have devised the apparatus disclosed in the 75 accompanying drawings, to which reference will now be had.

Figure 1 is a side elevation, showing the biplane and its parts diagrammatically. Fig. 2 shows a central axial section through the sleeve and gun. Fig. 3 shows a section along the line 3—3 of Fig. 2, and looking in the direction of the arrows, and Fig. 4 shows the apparatus applied to a mono-plane.

A represents a biplane, having the usual so-called "planes" B, and the usual framework with elevating rudder *a*, and also the steering rudders and propeller (not shown).

I do not make any claim to the special construction of the flying machine proper, as this is not part of my present invention, and this construction is well known in the art.

C represents the platform of the biplane, 100 on which are erected stanchions D, into which the trunnions *g* of the tube G are journaled. This tube is elevated and depressed through a small angle by means of suitable elevating gear, such as the curved rack *e'*, attached to the sleeve G, the pinion *e*² meshing in said rack and the hand wheel *e*³.

F represents the sight, which is attached to the side of the sleeve in any convenient 105

way. Any suitable sight may be provided for this purpose, preferably the well known telescope sight, with cross hairs mounted in the side of the sleeve.

5 The sleeve G is normally tilted at a considerable angle, since the gun platform would be always at an elevation, and generally at a considerable distance above the target. In order to protect the aeroplane 10 from injury from the blast of the gun, the lower end of the sleeve is made to project below the framework of the aeroplane, and also above said framework. In a biplane, the upper "plane" would be slotted fore 15 and aft to permit the passage therethrough of the sleeve G, and also to permit the sleeve to have the necessary motion about its trunnions to secure the desired elevation. In a biplane, it will be obvious that the sleeve 20 might be made shorter, and it will not be necessary to slot the "plane". This sleeve should preferably be made of light metal, just strong enough to serve as a launching tube for the gun, and to protect the occupants of the aeroplane from injury by the 25 lateral spread of the explosive gases, and also to prevent the aeroplane from being set on fire incident to the firing of the gun. Contained in this sleeve is a gun H, which 30 is attached to the sleeve by a friable connection, such as the set screw g'. This gun is made as light as practicable, preferably of some very tough and strong metal, such as vanadium steel, and it is not necessary that 35 the gun shall weigh much, if any, more than the projectile with its explosive charge. This gun is provided with a primer I, preferably an electric primer operated by a suitable source of electricity P, such as a dry 40 cell, the connections being completed by any suitable conductors p and p', and the circuit may be closed by any suitable switch Q. The powder in the gun K propels the projectile M, which has its chamber filled 45 with high explosive N, and any suitable kind of percussion fuse I' may be used.

The shell should be held in the gun by some friable connection, such as m, and the 50 resistance of shearing of the set screw g should be slightly in excess of the resistance required to start the shell in the bore, so that the shell begins to move forward before the gun starts to the rear; the idea being that the shell proceeds in the direction of the 55 target, and the powder gases in the gun will blow the barrel of the gun up through the top of the sleeve and in rear of the aeroplane, the gun being expended along with the projectile at each shot. By this arrangement 60 of having the gun and the projectile fly in opposite directions, comparatively small shock will be thrown on the framework of the aeroplane, and the sleeve may be used for several shots.

65 It will be obvious that the apparatus

should be so arranged that the resistance to the rearward travel of the gun in its sleeve should be approximately equal to the resistance of the projectile in its passage through the bore of the gun. Thus these two forces 70 would approximately neutralize each other, relieving the gun support of any heavy strain.

The sleeve is pointed downward and forward, which gives the advantage not only of being ready to fire when first approaching the target, and before those on the target have much chance of observing, much less injuring, the aviator; but an additional advantage is secured in that the velocity of the aeroplane is added to the velocity given to the projectile by the powder charge in the gun, and since gravity will also add to the velocity of the projectile, a comparatively small propelling charge, and consequently a 80 comparatively light gun, may be used. At the same time, a large enough projectile may be employed to carry a sufficiently large bursting charge, and also to have sufficient strength to penetrate the armor. 90

It will be obvious that the herein described apparatus may be installed on the rear portion of a dirigible balloon, the sleeve projecting rearward and clear of the gas bag, or other parts of the ship. 95

It will be obvious that various modifications might be made in the herein described apparatus, which could be used without departing from the spirit of my invention.

Having thus described my invention, what I claim and desire to secure by Letters Patent of the United States is:—

1. In a flying machine, the combination with a gun sleeve of a gun slidably mounted therein and adapted to pass rearwardly through and entirely clear of said sleeve, and a projectile adapted to move forward as the gun moves backward with approximately equal force whereby the strain on the gun support is reduced to a minimum, substantially as described. 100 105

2. In a flying machine, the combination with a gun platform of a sleeve trunnioned thereon, a gun connected to said sleeve by a friable connection, and a projectile containing a high explosive mounted in said gun, with means for firing said gun, substantially as described. 110 115

3. In a flying machine, the combination with a gun platform of a sleeve trunnioned thereon, an elevating gear for turning said sleeve through a limited angle in depression, a gun connected to said sleeve by a friable connection, and a projectile containing a high explosive mounted in said gun, with means for firing said gun, substantially as described. 120 125

4. An apparatus adapted for firing projectiles from flying machines, comprising a tube open at both ends, a gun mounted in 130

said tube and adapted to contain a projectile and a propelling charge, a severable connection between said gun and said tube, and means for firing said propelling charge whereby said projectile is discharged in one direction out of said tube, and said gun is expelled in the opposite direction entirely clear of said tube, substantially as described.

5. An apparatus adapted for firing projectiles from flying machines, comprising a tube open at both ends, a gun mounted in said tube and adapted to contain a projectile and a propelling charge, a severable connection between said gun and said tube, and means for firing said propelling charge whereby said projectile is discharged in one direction out of said tube, and said gun is expelled in the opposite direction entirely clear of said tube, with means for elevating 10 and depressing said tube, substantially as described.

10. An apparatus adapted for firing projectiles from flying machines, comprising a tube open at both ends, a gun mounted in said tube and adapted to contain a projectile and a propelling charge, a severable connection between said gun and said tube, and means for firing said propelling charge whereby said projectile is discharged in one direction out of said tube, and said gun is expelled in the opposite direction entirely clear of said tube, substantially as described.

15. An apparatus adapted for firing projectiles from flying machines, comprising a tube open at both ends, a gun mounted in said tube and adapted to contain a projectile and a propelling charge, a severable connection between said gun and said tube, and means for firing said propelling charge whereby said projectile is discharged in one direction out of said tube, and said gun is expelled in the opposite direction entirely clear of said tube, with means for elevating 20 and depressing said tube, substantially as described.

6. In a flying machine, the combination with a gun platform of a sleeve trunnioned thereon, a gun connected to said sleeve by a friable connection, and a projectile mounted in said gun, with means for firing said gun, substantially as described. 25

7. In a flying machine, the combination with a gun platform of a sleeve trunnioned thereon, an elevating gear for turning said sleeve through a limited angle in depression, a gun connected to said sleeve by a friable connection, and a projectile mounted in said gun, with means for firing said gun, substantially as described. 30

35 In testimony whereof, I affix my signature, in presence of two witnesses.

CLELAND DAVIS.
